UNITED STATES PATENT OFFICE.

THOMAS IRVING POTTER, OF PORTLAND, OREGON.

CHANGE COMPUTING AND DELIVERY MACHINE.

1,063,590.

Specification of Letters Patent.

Patented June 3, 1913.

Application filed December 27, 1911. Serial No. 668,031.

To all whom it may concern:

Be it known that I, THOMAS IRVING POTTER, a citizen of the United States, residing at Portland, in the county of Multnomah 5 and State of Oregon, have invented certain new and useful Improvements in Change Computing and Delivery Machines; and I do hereby declare the following to be a full, clear, and exact description of the same, 10 reference being had to the accompanying drawings, forming a part of this specification, and to the figures and letters of reference marked thereon.

This invention relates to change making 15 machines and is especially designed for the purpose of returning change or coins of small denomination for a deposited coin of larger denomination, the amount of change returned being automatically determined by 20 the size of the deposited coin. For example, a dime deposited will result in the discharge from the machine of two nickels; a deposit of a twenty-five cent piece will result in the discharge from the machine of one nickel 25 and two dimes. The change returned for each coin deposited is dependent directly upon the size or diameter of the deposited coin, and it is one of the objects of the present invention to provide a mechanism which 30 will eliminate wear on the coin and provide mechanical means under the control of the coin whereby the active functions of ejecting the change is performed.

The machine is more especially designed 35 for use in connection with the so called "pay-as-you-enter-cars" or for returning change to patrons of amusement places, the change always embodying coins of proper denomination for the payment of the entrance fee.

Referring to the accompanying drawings where one type of machine embodying the present invention is illustrated: Figure 1 is a front elevation of the machine with a portion 45 of the operating handle broken away. Fig. 2 is a sectional elevation in a vertical plane indicated by the line 2-2 in Fig. 1. Fig. 3 is a top plane view with upper wall of the casing removed and the front in section, some of the parts in this view being 50 broken away to show underlying parts. Fig. 4 is a detail plan of certain portions of the controlling and operating mechanism, with parts broken away and in section. Fig.

5 is a section looking toward the left of Fig. 55 1 substantially in the planes indicated by the dotted line 5-5. Fig. 6 is a view looking at the front of the operating mechanism immediately back of the chute plate, substantially in the plane indicated by the 60 dotted line 6-6 of Fig. 2. Fig. 6^a is a detail section in the plane indicated by the dotted line 6^a. Fig. 7 is a section in plane indicated by the line 7-7 of Fig. 6, with certain of the parts in elevation and the 65 chute plate and glass front in position. Fig. 8 is a detail section, on a somewhat larger scale of portions of the mechanism illustrated in Fig. 6. Fig. 9 is a section on the line 9-9 of Fig. 8. Fig. 10 is a section on the 70 line 10-10 of Fig. 8. Fig. 11 is a detail section on line 11-11 of Fig. 6 looking toward the right. Fig. 12 is a section on the line 12-12 of Fig. 6 looking toward the left. Fig. 13 is a rear elevation of the chute 75 plate with those portions of the mechanism which are mounted thereon, this view showing the opposite side of the operating mechanism from that shown in Figs. 6 and 8. Fig. 14 is a perspective view, partly broken 80 away and partly in section, illustrating the arrangement and operation of the parts for setting the selecting mechanism and for operating the selected ejectors, the frame and bearings being largely omitted.

Like reference characters indicate the 85 same parts in all the views.

The machine of the present invention embodies in its construction a coin chute in which coins of all denominations within the 90 capacity of the machine are deposited, and from which chute they may be discharged at the will of the operator either in a direction to reject them or, after they have exerted their control on the change returning mechanism, they are discharged from the chute into a suitable receptacle in the machine and out of reach of the attendant. In the manipulation of the mechanism, the deposited coin is detained in the chute by a movable 95 gate which is adapted to be displaced by the coin when the lever is advanced by the operator and the extent of such displacement effects the control of the change ejecting mechanism whereby the proper amount 100 of change is returned in exchange for the deposited coin. The connections between the movable gate and the coin ejecting mecha-

nism as embodied in the present machine are such that the actual work of ejecting the coins is performed by the operator through an independent chain of connections, but the 5 movement of the gate establishes the connections whereby the proper ejectors are operated.

Provision is made in the machine for preventing overthrow of the parts in order to 10 guard against the possible return of a greater amount than the value of the deposited coin.

Referring to Fig. 1 of the drawings, A indicates the front or door portion of a box 15 or casing (B) said door being preferably provided with a glazed opening (A') through which the coin stacks (C) and the coin chute together with the coin controlling portions of the gates may be seen whereby 20 the presence or absence and character of a coin in position in the chute may always be observed. At the lower portion of the casing there is provided a change cup (B') for the reception of the change returned for 25 the deposited coin and from which it may be removed by the person to whom it belongs. There is also provided in the bottom of the casing a tray or drawer (B²) for the reception of the deposited coins for which 30 change has been returned.

Immediately within the front of the casing and preferably at the left-hand side of the same there is mounted, what may be termed, the chute plate (D). This plate 35 has in its face, immediately adjacent the glass of the door appropriate channels forming a coin chute. At the upper end the channels merge in a single entrance chute (d) while at the lower portion the chute 40 branches, one branch (d') being adapted to conduct coins into the receptacles (B²) and the other branch (d²) into change cup (B') if it appears that the coin should be rejected or no change returned for it.

45 At the point where the branches (d' and d²) of the chute merge each branch is guarded by a gate. The gate (E) on the branch (d²) is adapted simply for withdrawal when it is desired that the coin de- 50 tained by it shall be rejected, but the gate (F) guarding the branch (d') is a movable member which determines by its engagement with the coin the amount of change to be returned for the coin. This gate (F) is in 55 the form of a flat plate or block mounted to slide in ways (f) in the chute plate and provided in its rear face with a projection (f') passing through a slot (f²) in the plate. Said pin constitutes one of the elements of 60 the chain of connections between the movable gate and the change ejecting mechanism, which will be hereinafter described.

Working in extensions of the ways (f) above the chute is a pusher (G) movable 65 toward and from the gate (F) and between

which and the gate (F) the deposited coin is positioned first, by the gate (E) and then by being gripped between the pusher (G) and gate (F). With this construction it is obvious that, if the pusher (G) be given 70 a reciprocation of definite length, the gate (F) will be moved a distance dependent upon the diameter of the particular coin between the pusher and gate.

The pusher (G) is provided with an inwardly extending projection or pin (g) preferably provided with an anti-friction roller (g') Fig. 9) adapted to work in a cam slot (h) in an oscillatory cam segment (H) carried by a shaft (H') mounted in bearings in the casing and having on its rear portion a crank arm (H²) connected by a link (H³) with the inner end (H⁴) of an operating lever or handle (H⁵). By depressing the handle (H⁵) it is obvious that the cam segment (H) will be rotated and the pusher advanced and again retracted upon the return of the handle to its normal position.

The coins to be returned as change for the deposited coin are held in coin stacks preferably connected together or formed in a casing (I) which may be removed from the machine when so desired, by grasping its handle (i). The coin stacks or receptacles 90 are adapted to contain coins of denominations indicated in Fig. 4, that is to say, the first three stacks counting from the left-hand end are adapted to contain five cent pieces and the fourth, fifth, and sixth stacks to contain 10¢, 25¢, and 50¢ pieces respectively. The stacks normally occupy a slightly inclined position, as shown in Fig. 5 and at the lower ends they are slotted for the passage 100 of ejectors (K). These ejectors are suitably mounted to reciprocate in a fixed frame (K') and are each provided on the lower side with a projection (k).

A rocking frame (L) journaled at the bottom of the casing in suitable bearings 110 (l) is formed at its upper edge with a slide way (L') in which works a selector bar (M). The selector bar is provided with upwardly extending projections (m) adapted to move in behind the projections (K) and when in position to engage with the projections, a forward movement of the rocking frame (L) will advance the ejectors and eject coins from the bottom of the stacks. By a proper formation and spacing of the 115 projections (m) any desired combination of the ejectors may be operated by adjusting the selector bar to proper longitudinal positions on the rocking frame and this adjustment of the selector bar is controlled by the 120 position of the movable member or gate (F) hereinbefore referred to.

The projection (f') on the gate or movable member (F) works in a slot (n) in the end of an arm (N) on a rocking shaft (N') 130

journalized in the casing. The shaft is provided with a downwardly extending arm (N²) in engagement through a pin and slot connecting (n') with a slide (N³). Said slide is provided with an arm or projection (N⁴) extending in a plane at right angles to the axis of the rocking frame (L) and working in a vertical slot (n⁴) in one end of the selector bar (M). The movement of the gate (F) is thus communicated to the selector bar and operates to directly adjust it to proper longitudinal position upon the rocking frame (L) and at the same time the connection between the slide (N³) and the selector bar is such that the rocking frame is free to move on its axis without changing the longitudinal position of the selector bar.

A rocking movement is imparted to the frame (L) from the shaft (H') by an arm (L²) carrying a downwardly extending link (L³) pivotally connected at its lower end with slide (L⁴) mounted in vertical ways (14) and provided with a cam groove (L⁵). (See dotted lines Fig. 2.) Working in the cam groove (L⁵) is a projection or anti-friction roller (15) mounted on one end of the rocking frame (L). The cam groove (L⁵) is so formed that during the first portion of the upward movement of the slide (L⁴) the rocking frame remains at rest, but during the final portion of said movement the rocking frame is swung toward the front of the machine so as to operate the ejectors. During the first portion of the movement referred to, the selector bar is positioned and during the final portion of the movement the ejectors are operated.

To prevent the movement of the rocking frame at any time when the projections (m) are not properly positioned with relation to the ejector a fixed index (O) is mounted on the casing in position to coöperate with a longitudinal projection (O') on the selector bar and form a stop except when the projection (O') is so positioned that the index may pass through one or the other of the slots or channels (o') in the projection. One of the slots or channels is preferably so positioned that the rocking frame may be swung forwardly when no coin is between the movable members of the coin chute and none of the projections (m) are in position to operate the ejector; thus when no coin has been deposited, the operating handle may make an idle stroke. When a coin of proper diameter is in position one of the slots (o') will register with the fixed index (O) and at such times the proper projection or projections (m) will be in position for advancing the ejector or ejectors to return change equaling in value the value of the deposited coin. A slug or coin of a different diameter from coins for which the machine is designed to return change will, of course, position the selector bar so that

no slot will register with the fixed index (O) and consequently the machine cannot be operated.

For returning the ejectors to normal position after being operated, the rocking frame for the selector bar is provided with a wing or wall (L⁶) lying in front of the projections (k') of the ejector as will be seen by reference to Figs. 4 and 5. The selector bar is also preferably but not necessarily provided with a spring (M⁶) for returning it to normal position as soon as it passes out of engagement with the fixed index. This spring not only insures the quick return of the selector bar to its normal position but it also causes the movable gate or member (F) to return to its normal position before the coin chute is opened by the upward movement of the pusher (G). Provision is made wholly independent of the spring, however, for returning these parts to their normal positions in a positive manner and in the preferred construction the returning devices also act as safety devices for locking the movable member (F) against overthrow due to momentum.

The mechanism for performing these functions embodies a locking plate (P) pivotally mounted on the projection (g) of the movable member (G). This locking plate (P) works in proximity to the inner face of the chute plate (D) and is best seen in Figs. 6, 8, and 13. In its lower portion it is provided with a relatively large opening (p) through which the projection (f') extends. The bottom edge or wall of the opening forms a stop against which the projection (f') will strike when the two movable members (G and F) are separated to their maximum distance as shown for instance in the front elevation Fig. 1 and in full lines in Fig. 13. The lock plate forms as it were a loose connection whereby when the member (G) is elevated to its highest position the member (F) will be returned to its normal or highest position but the member (G) may be depressed without movement of the member (F) as downward movement will only be imparted to the latter when a coin is interposed between the members.

The lock plate (P) is provided with a series of ratchet teeth (p') adapted to engage a tooth formed by cutting away the sides of the projection (f') at the proper angle (Figs. 6, 8 and 13). The teeth (p') are normally held so as to engage the projection (f') by spring (p²) bearing against one side of the lock plate (P) and the teeth are preferably so cut that one of them will engage the projection (f') at each position where the coin will just fill the space between the two movable members (F—G) with the result that no matter how quickly the machine may be operated the momentum of the parts cannot carry the lower member away

from the upper member when the coin is held between them. In order to release the locking plate from the projection (f') the cam segment (H) is provided with a projection which may be in the form of a screw (p³) adapted to coöperate with the side of the locking plate opposite the spring and teeth so as to press said plate away from the projection (f') at the moment when the cam segment reaches the extreme of its forward movement. When so freed from the projection (f') the locking plate is caught and held against the tension of its spring (p²) by a pivoted catch (p⁴) mounted on the inner face of the chute plate and having a shoulder (p⁵ Fig. 8) to retain the locking plate in its released position as indicated in dotted lines in Fig. 13 until it is drawn up above the catch (p⁴) to the position indicated in full lines. The upper edges of the catch and lower edge of the locking plate are inclined or beveled so as to permit the locking plate to travel downwardly.

Under some circumstances, as for instance on making a short stroke, the projection (p³) might not be effective to release the locking plate and in order to guard against this contingency the locking plate is provided on one end with a cam projection (P') with which a pivoted dog (P²) is adapted to engage to swing the plate on its supporting projection (g) during the upward movement of the locking plate, the position when the dog begins to act to swing the plate being indicated by the full line position of the dog, and the dotted line position of the plate in Fig. 13. During the downward movement of the plate the dog (P²) will be swung against the tension of its spring to the position indicated by the dotted lines and the plate itself will not be swung on its supporting projection.

The operation of this portion of the mechanism is briefly as follows: Assuming that a coin which is of smaller diameter than the normal distance between the two movable members is in position in the coin chute, when the operating handle is pressed downward the upper member (G) will travel until it comes in contact with the coin and during such movement the locking plate will travel downwardly past the projection (f') and at the time when the coin limits the relative movement of the members (G—F), said locking plate will be in position to engage with the projection (f') so as to maintain the movable members (F—G) in their relative positions during their continued downward movement. Just as the end of the forward movement of the cam segment is reached the locking plate will be tripped from the projection (f') by the part (p³) and held out of engagement by the catch (p⁴). When the locking plate is released the roller (g') on the projection (g) moves

into the reverse curve or opposite incline (h⁵) at the lower end of the cam groove (h) thereby imparting to the upper movable member (G) a slight reverse movement to release the coin and permit it to drop into the branch (d') of the coin chute and during this reverse movement the member (F) is held by the engagement of the selector bar with the fixed index.

The deposited coin is retained in position between the movable members (F—G) and in plain view of the attendant before operating the machine by detent or gate (E) which is preferably formed by a forwardly bent flange on a plate or flat frame (R) pivotally mounted on the inner face of the chute plate and projecting forwardly through a slot or opening in the plate as shown clearly in Figs. 1, 7 and 13. The gate is held advanced or in its normal position so as to block the entrance of the coin into the branch (d²) by a coiled spring (r) and it is only adapted to be retracted or withdrawn against the tension of the spring when the operating handle is given a reverse or upward movement from its normal position. When so moved upwardly the operating handle imparts to the cam segment (H) a reverse movement and the edge of the cam segment rides under an arm (R') on the gate thereby retracting or moving the gate from the position shown in full lines to that shown in dotted lines in Fig. 7, such movement opening the branch (d²) of the chute to permit of the coin passing directly through the same and out into the change cup (B').

In order to retain the coin in full view of the attendant and depositor even after the change has been returned for the same so as to avoid any possible dispute with respect to the value of the deposited coin, a gate or detent is provided in the branch (d') in the chute at the point below the entrance to that branch. This gate or detent is indicated by the reference letter (S) and is in construction quite similar to the gate (E) being similarly pivoted on the inner face of the chute plate so as to project forwardly through a slot or opening in the plate extending transversely of the chute. It is held advanced or in a position to intercept a coin passing into the branch (d') by a spring (s) best seen in Fig. 11 and is retracted by a heel (s') of the arm (N) when the lower movable member (F) reaches the highest position of its movement. The coin discharged from between the movable members (F—G) will therefore be caught and held by the gate (S) until the completion of the return movement of the operating handle when the gate (S) would be withdrawn and the coin allowed to pass down into the receptacle (B²).

The normal position of the operating handle is determined by the movable stop

which will normally arrest its upward movement but may be depressed by the attendant when it is desired to give the handle an abnormal upward movement, for instance, to 5 retract the gate (E) and reject a coin that has been deposited but for some reason is objectionable or not such a coin as the machine is adapted to handle.

Any suitable stop may be employed but 10 that preferred is illustrated in Figs. 6 and 6^A. It consists essentially of a block of fiber or other non-metallic substance (T) fixed on the inner face of the casing wall above the operating handle and a pivoted block (T') 15 mounted on the handle itself and controlled from the outside of the casing by a finger piece (t) located in position to be readily depressed by the operator's thumb when he desires to lift the handle beyond its normal 20 position. As a convenient construction the stop (T') may be mounted on the inner portion of a shaft (t') journaled in bearings upon the operating handle and a suitable spring of any preferable construction may 25 be employed for returning it to the upright position, shown in full lines in Fig. 6^A, after it has been turned down to the dotted line position for the purpose of permitting an abnormal upward movement of the handle.

30 To assist in returning the parts after the operating lever or handle has been depressed, a coil spring (U) is attached to the inner face of the casing at one end and at the opposite end secured to the inner end of the 35 operating lever, or in the preferred construction secured to a hook-shaped block (U') which engages the upper edge of the lever and is retained in position by pins (u) and a fixed stop (u'), the construction being such 40 that the spring (U) will exert its tension to return the operating lever to normal position, but the stop (u') will prevent the spring from lifting the outer end of the operating lever above its normal position.

45 With this construction even though the movable stop (T') should have been displaced the abnormal upward movement of the operating lever must be effected by the attendant and can never occur automatically under the influence of the returning spring.

The members (F and G) constitute in effect measuring devices whereby the diameter of the deposited coin is measured and by the connections controlled by one of the 55 said members the proper ejectors are operated for returning change in value the equivalent of the deposited coin as determined by its diameter. It therefore becomes unnecessary to provide more than a 60 single measuring mechanism and all coins are deposited in the same entrance chute.

In operation, a coin is deposited in the chute and when it has been inspected by the attendant, the operating lever is depressed 65 resulting first in a downward movement of

the member (G) until the same contacts with the coin when through the coin itself the lower member (F) is forced downwardly thereby positioning the selector bar, continued downward movement of the operating lever serving to swing the frame (L) together with the selector bar forwardly to operate the selected ejectors.

The particular machine illustrated is adapted for handling United States currency and is designed for returning change for a dime, 25¢, 50¢ and \$1. Under these conditions, the smallest amount of change returned is two 5¢ pieces for a dime and one 5¢ piece and two dimes for 25¢. Therefore 70 it is most convenient to arrange the ejectors so that the ejector for the first two stacks move in unison and they are conveniently connected together. The same is true of the ejectors for the third and fourth stacks, as 75 is indicated clearly in Figs. 4 and 6 where it will be seen that a single projection (k) is adapted to operate each pair of the ejectors. The fourth ejector, *i. e.* that for dimes, is adapted at each operation to eject two dimes 80 instead of a single one. The projections (m) (Fig. 4) on the selector bar are so positioned that a longitudinal movement of the bar toward the right will first bring the left-hand projection into position to coöperate with the first pair of ejectors thereby 85 returning two 5¢ pieces for a dime. The second projection (m) is adapted to come into position to engage the projection (k) on the second pair of ejectors when the movable members (F—G) are relatively positioned by a 25¢ piece at which time the first projection has moved out of position to engage with the first pair of ejectors with the result that the operation of the machine will 90 discharge two dimes and a nickel.

The continued movement of the selector bar toward the right (Fig. 4) as determined, for instance, by a 50¢ piece between the members (F and G) will bring the third 95 projection (m) into position to coöperate with the 25¢ ejector, but the second projection still remains in position to coöperate with the 10¢ and third 5¢ ejectors so that the operation of the machine will result in the 100 ejection of one 25¢ piece, two 10¢ pieces and one 5¢ piece. Further movement as determined by a one dollar coin between the members (F and G) will bring the last projection (m) on the selector bar into position 105 to coöperate with the 50¢ ejector while the two intermediate projections (m) are still in position to coöperate with the 25¢, 10¢ and third 5¢ ejectors resulting in the ejection from the machine of one 50¢, one 25¢, 110 two 10¢ pieces and one 5¢ piece, this being 115 the proper change for one dollar.

Obviously the projections (m) and (k) may be arranged to give any desired combination for operating the ejectors, but this 120

portion of the apparatus constitutes a separate invention which is not claimed specifically herein.

What I claim as new is:—

- 5 1. In a change calculating and ejecting machine, the combination with a plurality of coin stacks, an ejector for each stack and a single chute for deposited coins of all denominations for which change is desired, of
 10 two members movable relatively toward and from each other in said chute for gaging the diameter of a deposited coin of any denomination, means for moving said members simultaneously in the same direction and connections intermediate one of said members and the ejectors whereby the ejectors to be operated are selectively determined by the diameter of the deposited coin.
2. In a change calculating and ejecting machine, the combination of a plurality of coin stacks, an ejector for each stack, a single coin chute for the reception of coins of all denominations for which change is desired, members movable relatively toward and from each other in said chute for gaging the diameter of all coins deposited therein, means for moving said members relatively toward each other and for moving said members simultaneously different distances in the same direction when their relative movement is arrested by interposed coins of different diameters and connections controlled by one of said members for selectively determining which of the ejectors shall be operated in accordance with the diameter of the coin between said members.
3. In a change calculating and ejecting machine, the combination with coin stacks and ejectors, and a controlling mechanism for the ejectors embodying members movable relatively toward and from each other, and simultaneously in the same direction, of a single chute for retaining deposited coins of all denominations between said members, means for moving said members toward each other until arrested by the interposed coin and for moving the members simultaneously different distances when their relative movement is arrested by coins of different diameters and selective connections controlled by the member moved by the interposed coin for operating the ejectors.
4. In a change calculating and ejecting machine, the combination with coin stacks and ejectors and a chute for deposited coins, of members movable toward and from each other in said chute for gaging the diameter of the deposited coin and simultaneously in the same direction to control the ejecting mechanism, means for locking said members against movement away from each other, means for moving said members simultaneously in same direction when locked together, connections intermediate one of said members and ejecting mechanism and

a trip for releasing the locking mechanism to permit of the discharge of a coin held between the members.

5. In a change calculating and ejecting machine, the combination with coin stacks, an ejector for each stack and a chute for coins for which change is desired, of members movable relatively toward and from each other in said chute and between which a deposited coin is adapted to be held, means for moving one of said members toward the other, a lock for connecting said members when their relative movement is arrested by an interposed coin, means for moving said members simultaneously when locked together, a trip for releasing said lock during reverse movement of members and connections intermediate one of said members and ejectors for determining which of the ejectors shall be operated in accordance with the diameter of the coin held between said members.

6. In a change calculating and ejecting machine, the combination with coin stacks, an ejector for each stack, a chute for coins for which change is desired, and members movable relatively toward and from each other in said chute for gaging the diameter of a coin interposed between said members and a movable detent for retaining a coin in position between said members, connections intermediate one of said members and ejectors for determining which of the ejectors shall be operated in accordance with the diameter of the deposited coin and an operating lever with connections whereby a movement of the lever in one direction from normal will operate the movable members and ejectors and a movement in the opposite direction from normal will retract the detent to permit of the rejection and discharge of the deposited coin.

7. In a change calculating and ejecting machine, the combination with coin stacks, an ejector for each stack and a coin chute for deposited coins for which change is desired, of relatively movable members between which the deposited coin is gaged in diameter, connections intermediate one of said members and ejectors for determining which ejectors shall be operated, means for releasing a coin held between said members, a movable detent for coins discharged from between the members and means for successively operating said members and detent whereby the coin discharged from between the members will be retained in view during the return of the members to normal position.

8. A change calculating machine embodying a coin chute for the reception of coins for which change is desired, a member movable transversely of said chute and adapted to control the amount of change ejected from the machine, a pusher mov-

70

- able toward and from the first mentioned member whereby a coin interposed between the said pusher and member will advance the member in proportion to the diameter of the coin and means for holding the said member against return movement during the initial return movement of the pusher whereby a coin held between the members is released.
10. 9. A change calculating machine embodying members movable relatively toward and from each other and simultaneously in the same direction, means for positioning a coin between said members whereby their relative position is determined, means for moving said members simultaneously in one direction while positioned by an interposed coin and means for temporarily retarding the movement of one of said members during the initial return movement of said members whereby a coin held between the members is released.
10. In a change calculating machine, the combination with a coin chute having independent discharge branches and a movable detent guarding one of said branches, members movable relatively toward and from each other and simultaneously in the same direction to transfer a coin into position for discharge in the branch of said chute not guarded by the detent, ejecting mechanism controlled by the relative position of said members, means for advancing one of said members toward the other to grip the interposed coin and transfer the same by a simultaneous movement of the members in the same direction, and means for withdrawing the detent by a reverse movement of the said member advancing means.
40. 11. In a change making machine, the combination with a chute for deposited coins for which change is desired, members movable in said chute toward and from each other and simultaneously in the same direction, ejecting mechanism controlled by one of said members and an operating lever, of a segment having a cam thereon for operating the other of said members whereby a coin interposed between the members will cause one to be operated by the other and a lock connecting said members when their relative position has been determined by an interposed coin.
55. 12. In a change calculating and ejecting machine, the combination with stacks for coins, an ejector for each stack, an operating lever and a chute for deposited coins for which change is desired having a single entrance and two discharge branches, of independent movable detents in said
- branches, members movable in said chute above said detents for gaging the diameter of the deposited coin, connections intermediate one of the said members and the ejectors, and independent operating connection intermediate said detents and operating handle whereby the detents are withdrawn by movements of the handle in opposite directions, respectively, and the deposited coin may be discharged through either branch of the chute at the will of the operator.
13. In a change calculating machine, the combination with a coin chute, members movable in right lines in said chute toward and from each other and simultaneously in the same direction, a cam segment for moving one of said members toward and from the other, ejecting mechanism controlled by the other of said members, a locking mechanism between said members embodying a rack bar and tooth whereby the members may be locked together when their relative position is determined by an interposed coin and a projection moved by the cam segment for releasing said lock for permitting the members to separate for the discharge of the interposed coin.
14. In a change making machine, a coin chute having a single entrance and two discharge branches, two independently movable gates, one normally closing the entrance to each branch in position to direct a coin into the other branch, coin ejecting mechanism controlled by the movement of one of said gates, means for manually operating the gates independently of each other, a third gate located in the branch below the ejector controlling gate, means for operating it and a transparent cover for said chute and gates whereby coins detained by all the gates may be observed.
15. In a change making machine, the combination with a coin chute having a single entrance and two discharge branches, a gate guarding the entrance to each branch and an operating handle with operating connections whereby movement of the handle in one direction will operate one gate and movement in the opposite direction will operate the other gate, of a movable stop for holding the handle against movement in one direction, means for displacing said stop, coin stacks and ejectors and means for selectively controlling the ejectors operated by one of said gates.

THOMAS IRVING POTTER.
